TEMPLE ROLLER

Adam Schaffer, Philadelphia, Pa.

Application March 14, 1935, Serial No. 11,148

7 Claims. (Cl. 139—296)

The present invention relates to looms, and more particularly to an improved temple roller for counteracting the tendency of the cloth to draw in and become narrow and to hold the cloth 5 extended to the full width of the reed during the operation of weaving.

In practice a pair of temples is used, one at each side of the cloth, and each temple is provided with a pair of rollers, in one or more sections, having peripheral pins, rubber spiral and wire ribs, cork layers and the like.

These prior temple rollers are not only very expensive in the operation of the looms on account of their costly manufacture but also because they wear down rapidly and require frequent replacement and cannot be economically repaired, and further they are not adapted for working on silk and other delicate cloth woven in the loom.

An object of this invention is to overcome these deficiencies and disadvantages and to provide a temple roller which is cheap to initially manufacture, which may be economically recovered or renewed, which has increased wearing qualities 25 over prior rollers and which may operate upon silk and other delicate fabric without injury thereto.

Another object of the invention is to provide a temple roller with a relatively soft gripping 30 surface which is effective, which may withstand relatively long wear, and which is economically renewable without discarding the core or body portion of the roller.

A further object of the invention is to provide 35 a temple roller with a core of hard wood or the like having wound thereon a braided cord strand of cotton, leather, rawhide or other suitable material; the core being so constructed and the strand layer being so placed on the core as to 40 interlock the ends of the strand to the core and cover and protect the strand ends beneath the winding and prevent the ends protruding and dangling from the finished roller; and to also hold the winding taut to the desired degree, depending upon the material of the fabric to be 45 held, so that the strand presents a spiral tight winding at the peripheral surface of the roller.

Another object is to provide a roller structure 50 of this character wherein the roller may be of desired length so as to be used as a full length roller or in multiple where separate roller sections are desired and wherein the spiral winding may be made in either direction.

Another object of the invention is to provide 55 a roller of this improved type which may be

readily substituted for present day rollers in the cup of the temple bar without any modification in the construction and proportions of the same.

With the foregoing and other objects in view, the invention will be more fully described hereinafter, and will be more particularly pointed out in the claims appended hereto.

In the drawing, wherein like symbols refer to like or corresponding parts throughout the several views,

Figure 1 is a perspective view of a temple as applied to one side of a strip of cloth and equipped with rollers constructed according to the invention.

Figure 2 is a longitudinal section taken through the same on the line 2—2 of Figure 1.

Figure 3 is a transverse section taken on the line 3—3 of Figure 2.

Figure 4 is a bottom plan view of the cap of the temple bar, showing the mounting of a pair of 20 the improved rollers therein.

Figure 5 is a like view, showing a slight modification of the roller arrangement and wherein sectional rollers are used.

Figure 6 is a detail perspective view of a roller core having a portion of the winding layer applied thereto and with the initial end of the winding interlocked to the core, and

Figure 7 is a perspective view of the core having the winding layer substantially completed, 30 and showing the last operations in locking and covering the finished end of the winding.

Referring now to the drawing and first to Figure 1, 15 designates a temple bar having a supporting arm 16 adapted to be attached to the breast beam of the loom, or the like so as to support the bar 15 with its parallel cups 17 transversely beneath the edge portion of the cloth fabric 18 as it comes from the reed of the loom. The bar 15 carries a cap piece 19 which is detachably connected at its outer end to the outer end of the bar 15 by a screw 20 or the like and supported in spaced relation from the bar 15 to provide a slot or passage through the temple bar 40 and through which the edge portion of the cloth 45 or fabric 18 travels.

It is well known in the art to provide a pair of temples one at each edge portion of the cloth to hold the latter taut and prevent the narrowing of the cloth as it passes out of the loom.

The cap 19 carries a pair of temple rollers which are of like construction, as shown in Figure 4, and which are disposed in parallel slightly spaced apart relation so as to register with the cups 17 when the cap 19 is fitted to the bar 15.

Each temple roller comprises a core 21 of any suitable material, such as relatively hard wood and the core 21 has an axial opening 22 extending entirely through the same for the reception 5 of an axle pin 23 which at one end is provided with a smooth and rounded portion adapted to engage in a seat 24 provided at the outer end of the cap 19, the axle rod 23 having a screw threaded portion 25 which detachably engages with a 10 threaded opening through the inner end of the cap 19. There is a rod 23 for each temple roller and the latter may be quickly and easily removed from the cap, after the same is detached from the bar 15, by merely unscrewing the rod sections 15 25 and withdrawing the rods from the cores 21. Each core 21 is provided at opposite ends with kerfs 26 and 27 which are disposed transversely across the ends of the core and at one side of the axial opening 22, as shown in Figures 6 and 7. 20 The surface layer of the roller may be of braided cotton, leather, rawhide or other suitable material which is pliable and which presents the necessary frictional contact for holding the fabric 18. These new temple rollers are adapted 25 particularly for silk, cellulose or other fabrics of a delicate nature so that the fabrics would not be injured by the temples. The surface layer in the present instance comprises a spiral winding 28 which extends from substantially end to end about the core 21 and is drawn tightly thereabout during the winding to provide a compact and even surface to the roller of the desired hardness, depending upon the goods to be passed through the temple. The winding is in the form 30 of a strand, of leather, rawhide, braided cotton or the like which has its initial extremity 29 disposed in flat engagement against one side of the core 21, near one end thereof, and which is carried from said extremity 29 through the adjacent end kerf 26 of the core to form an end loop 30 for the winding, the strand being carried from the kerf 26 about the core 21 in successive convolutions or helices so as to not only cover the core but also bind the convolutions of the strand 35 about the initial end 29. Thus, the extremity 29 is firmly held and enclosed within the winding and the looped end 30 engages through the kerf 26 to lock the initial end of the layer winding on the core 21. 40 The strand 28 is wrapped spirally and continuously until adjacent the opposite end of the core 21. Here the end portion of the strand 28 is looped outwardly from the side of the roller to form a finishing loop 31 which is of considerable 45 size to admit of ease in finishing off the end of the winding. The end of the loop 31 is engaged through the kerf 27 and is held against the side of the core 21 while the finishing loop is twisted and rolled about the end portion of the core and over the flat end of the loop so as to hold the end against the core and cover it by the adjacent end convolutions of the winding. After the finishing loop 31 has been twisted and drawn about 50 the core 21 until the finishing loop 31 is too small for further wrapping, the finishing extremity 32 of the strand is drawn lengthwise and along one side of the roller so as to pull the free end of the loop 31 through the kerf 27 and draw the strand taut so that the finishing end of the roller 55 will be substantially the same as the initial end thereof. After the strand has been drawn taut and the finishing loop 31 has disappeared, the extremity 32 is cut off close to the adjacent end windings so that the cut end of the strand 60 will lie beneath the end convolutions of the wind- 75

ing and will be housed and held in locked position on the core.

These temple rollers may be of any desired length. As shown in Figures 1 to 4, they are of the full length of the cups 17 but, as shown in Figure 5, the rollers may be of shorter length, depending upon the side of the cores 33 and 34 so as to interfit in offset or staggered pairs, according to the different types of cloth and work to be done.

It is apparent that when the surface of the roller is worn, the strand 28 may be cut or otherwise removed from the core 21 and a new surface layer strand may be quickly and easily wound upon the core to renew the surface of the roller. The cores may thus be saved and used indefinitely as the winding of the strand 28 is a relatively simple and economical operation, and the strand itself, whether of cotton, leather or rawhide is relatively inexpensive. This obviates the necessity of discarding the rollers completely and the consequent high cost of maintenance of the temple rollers.

It is obvious that various changes and modifications may be made in the details of construction and design of the above specifically described embodiment of this invention without departing from the spirit thereof, such changes and modifications being restricted only by the scope of the following claims:

What is claimed is:—

1. A temple roller, comprising a core having kerfs in its opposite ends, and a surface layer winding of a soft pliable material extending spirally from end to end on the core and having its opposite ends locked through the kerfs with the opposite extremities of the winding terminating beneath the respective end helices of the winding.

2. A temple roller, comprising a core having kerfs in its opposite ends, and a surface layer winding of a strand of pliable material wound spirally from end to end on the core, the initial end of the wound strand being anchored beneath the several first helices thereof and looped axially from beneath the same through the adjacent kerf of the core and lock the winding thereto, the finished end of the winding being looped through the kerf at the opposite end of the core and returned beneath the several adjacent end helices of the winding to lock the end of the winding to the core, said opposite end helices of the winding enclosing and covering the opposite ends of the layer winding.

3. A temple roller comprising a core of relatively hard wood having kerfs in its opposite ends, a strand of relatively soft and pliable material wrapped about said core from end to end thereof and having its opposite end portions looped outwardly through said kerfs and with the extremities of the strand disposed beneath the adjacent end helices of the winding for holding the extremities beneath the surface of the roller and taut through said kerfs.

4. A temple roller comprising a core having kerfs in opposite ends, and a strand of braided cotton wound spirally from end to end on said core and with the opposite ends of the strand looped outwardly through the kerfs and the extremities of the strand lying beneath the convolutions of the winding.

5. A temple roller comprising a core having an axial opening therethrough and transverse kerfs in opposite ends and offset from said axial opening, and a surface winding of a strip of pliable material extending from end to end about the

core and with the end portions of the strip looped outwardly through said kerfs and with the extremities of the strip disposed beneath the adjacent end convolutions thereof.

- 5 6. A temple roller comprising a core having an axial opening therethrough for receiving a supporting pin and provided with offset kerfs in its opposite ends, and a renewable surface winding comprising a strip of pliable material wound helically from end to end about the core, the opposite ends of said strip being looped outwardly through said kerfs and with the extremities disposed beneath the adjacent convolutions of the strip.
- 10 7. The method of covering the core of a temple roller having kerfs in its opposite ends, which consists in looping one end of a pliable strip through the kerf at one end of the core and spirally winding the strip about the roller from said

end and over the adjacent extremity of the strip to cover the latter, continuing the spiral winding of the strip throughout substantially the length of the roller, engaging the opposite end portion of the strip through the kerf in the opposite end of the roller with a loop portion between the last convolution and the kerf, twisting said loop portion and winding the same about the core to provide the final convolution in the winding and wrapping said convolutions over the adjacent extremity of the strip to cover the same and hold it firmly to the core, then drawing said extremity of the strip outwardly beneath said final convolution of the winding to draw the winding taut, and finally severing the extremity of the strip 15 adjacent said convolutions for completely covering the final extremity of the wound strip.
